United States Patent Office

Des. 233,104
Patented Oct. 8, 1974

233,104

SOAP DISH STAND OR SIMILAR ARTICLE

David P. Zagaroli, Hickory, N.C., assignor to Ajax Hardware Corporation, City of Industry, Calif.

Filed Mar. 14, 1973, Ser. No. 341,021

Term of patent 14 years

Int. Cl. D6—04

U.S. Cl. D6—89

Fig. 1.

Fig. 2.

Fig. 3.

Fig. 4.

Fig. 5.

FIG. 1 is a perspective view of a soap dish stand or similar article showing my new design;

FIG. 2 is a top plan view on an enlarged scale;

FIG. 3 is a front elevational view thereof;

FIG. 4 is a side elevational view; and

FIG. 5 is a bottom plan view.

I claim:

The ornamental design for a soap dish stand or similar article, as shown and described.
